CLAIM

The ornamental design for a pet leash as shown and described.

DESCRIPTION

FIG. 1 is a perspective view of a pet leash showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front view of the pet leash, in a state of use, thereof;

FIG. 9 is a left, front perspective view of the pet leash, in a state of use, thereof;

FIG. 10 is a front, right perspective view of the pet leash, in a state of use, thereof; and,

FIG. 11 is a front, right perspective view of the pet leash, in a state of use, thereof.

FIGS. 1, 2, 3, 6 and 7 contain a symbolic break and the portion between the break lines forms no part of the claimed design. The dot-dash-dot lines represent stitching that form no part of the claimed design. The dotted lines represent portions of the pet leash that form no part of the claimed design. The dotted lines in FIGS. 8, 9, 10 and 11 represent environment that form no part of the claimed design. The dash-dash-dash boundary in FIGS. 8, 9, 10 and 11 represent a boundary box that forms no part of the claimed design.

1 Claim, 7 Drawing Sheets
